UNITED STATES PATENT OFFICE.

HARRIET LYONS REDMOND, OF BOSTON, MASSACHUSETTS, ASSIGNOR TO THE WILLIAM CARTER COMPANY, OF NEEDHAM HEIGHTS, MASSACHUSETTS, A CORPORATION OF MASSACHUSETTS.

INFANT'S BAND.

Application filed January 31, 1923. Serial No. 616,057.

To all whom it may concern:

Be it known that I, HARRIET LYONS REDMOND, a citizen of the United States, and a resident of Boston, in the county of Suffolk and State of Massachusetts, have invented an Improvement in Infants' Bands, of which the following description, in connection with the accompanying drawings, is a specification, like characters on the drawings representing like parts.

This invention relates to undergarments and particularly to infants' knitted shirts or so-called abdominal bands, although within the scope and purpose of my invention it may be put to other uses.

In order that the principle of my invention may be clearly set forth I have disclosed certain embodiments thereof in the accompanying drawings, wherein—

Fig. 1 is a front elevation of an infant's undershirt or band disclosing the preferred embodiment of the invention;

Fig. 2 is a side elevation of the same;

Fig. 3 is a side elevation, partly in section, showing the lower portion of the shirt or band folded upon the front and back vertical median lines of Fig. 1;

Figure 4 is a view similar to Figure 3 but viewing the garment from the front;

Fig. 5 is a front elevation similar to Fig. 1 and showing the lower portion of a modified form of band;

Figs. 6 and 7 are partially diagrammatical front and back elevations respectively, illustrating the manner of attaching to the shirt a diaper or napkin of triangular form;

Figs. 8 and 9 are front and back elevations respectively illustrating another manner of attaching a similar diaper; and

Figs. 10, 11 and 12 are respectively front, back and side elevations of the band with a different diaper attached.

Referring more particularly to the drawings and first to that form of my invention shown in Figs. 1 to 4 I have indicated the trunk or body portion of the undergarment at 1 the same being preferably of knitted material whereof the wales 2 extend vertically or lengthwise of the body portion of the garment. Desirably the garment is formed by rib knitting as a cylindrical or seamless tube having integral shoulder straps 3, 3 at the upper extremity. The garment herein is provided with a suitable reen-

forcing edge formation 4 constructed by 55 overseaming or like sewing operation so as to form an elastic seam. The edges of the shoulder straps and neck portion are similarly seamed as indicated at 5, 5.

While the garment may be otherwise employed it is primarily intended as an infant's band and to that end has at its lower extremity a formation or formations adapting it for the attachment thereto of some suitable article such as an infant's napkin 60 or diaper. For this purpose the garment is preferably provided at its lower extremity with integral strip continuations at both front and rear and positioned approximately centrally of the lower edges of the 65 band. Such continuations or tabs indicated at 6 and 7 respectively, are desirably integrally knitted with the body portion of the garment, having wales 8 extending in the same direction as in said body position. 70 The overseaming 4 for the lower portion of the band desirably extends uninterruptedly about the edges of said tabs 6 and 7.

Said tabs 6 and 7 are themselves preferably reinforced, as by securing upon the 80 face thereof, and desirably the inner face, one or more layers of knitted cotton or other fabric 9 and 10 respectively, as clearly indicated in section in Fig. 3 and in full in Fig. 4, the wales 11 of said layers extending herein in the same direction as those of the tabs. As seen in Fig. 4 said reinforcing layers have their edges included in the overseaming 4, the upper straight edge of said reinforcements desirably being left free 85 90 as indicated at 12.

It is highly desirable that an infant's band be adapted for use with infants' diapers or napkins of different style or type and with different methods of folding and 95 attaching the same. For this purpose I have provided in addition to the attaching means or tabs 6, 7, above described, additional reinforcing and supporting portions or patches for the reception of pins or like attaching means and positioned at the lower extremity of the garment at points spaced from said tabs. Two of such reinforcing sections or patches are indicated at 13 and 14 in Figs. 1, 2 and 3 and in section in Fig. 4. Said patches preferably comprise one or more layers of knitted fabric secured to the garment as by means of the elastic seaming 100 105

indicated at 15. As shown said patches are placed upon the inner surface of the garment giving a more pleasing and finished appearance thereto. Obviously, however, they may be secured upon the outer surface of the band.

Said patches or reinforcing and supporting areas are desirably of the form illustrated being of greater dimension in the direction of their height and longitudinally of the garment. By thus forming said patches of relatively great height as compared to their width and extending upwardly upon the body portion of the garment for a substantial distance the garment is more readily adapted for wear by infants of different body length, the pin or other attaching means being fastened at any desired point longitudinally of said patches. As clearly seen in Figs. 2 and 3 the wales of said patches indicated at 16 extend lengthwise of the body portion, said patches thus presenting little or no interference to the normal elasticity of the body portion while aiding materially in maintaining the proper shape of the band.

In Fig. 5 I have shown a modified form of garment having a trunk portion indicated at 1' and having side reinforcing portions or patches 13', 14'. In this instance I omit the depending tabs at front and rear of the garment, this form of band being particularly adapted for use with the square form of diaper indicated in Figs. 10 to 12, and with said form only.

Referring now to Figs. 6 and 7 I have illustrated the band 1 with attached diaper or napkin. In this instance the central front and rear tabs 6 and 7 are each in lowered or depending position. The diaper 17 here employed is shaped or folded into triangular form, the long upper edge thereof, indicated in dotted lines at 18, being applied to the lower portion of the band, preferably upon the inner surface thereof and with its transverse central point adjacent the vertical median line of the back of the band.

The two upper corners of the diaper are brought together across the front of the band and overlapped at the center thereof, the third or lower corner being brought up between the legs of the infant and adjacent and preferably beneath the front tab 6. A pin 19 or other attaching means secures the several portions of the diaper to said tab 6. At the rear, Fig. 7, the diaper is desirably fastened to the tab 7 by a similar fastening means, shown as the pin 20. The diaper may be and preferably is secured to the band at the sides thereof as by the pins 21, 22 passing through the reinforcing patches 13 and 14 respectively.

In Figs. 8 and 9 I have shown the shirt or band 1 with attached triangular diaper 17 similar to that illustrated in Figs. 6 and

7. In this instance, however, the central front and rear tabs are each reversed or folded back upon the band, either upon the inner or outer surface thereof. Front and rear fasteners or pins 23, 24 are respectively passed through the tabs 6 and 7 and through the adjacent portion of the band and diaper. Pins or other fasteners 25, 26 may if desired be fastened through the patches 11, 12, as in Figs. 6 and 7.

It will be noted that the manner of attachment shown in Figs. 8 and 9 brings the napkin higher upon the body of a wearer of the same body length as compared with Figs. 6 and 7, thus providing a snug fit about the hips or above. The side patches 13, 14 being of elongated form extending well up the trunk of the garment accommodate the same to this method of diaper attachment. By bringing the diaper higher upon the body of the infant extra protective covering and warmth is afforded for the abdomen. The elongated formation of the patches 13, 14 affords wide latitude in the location of the fasteners for the diaper, thus accommodating the shirt to various body lengths of infants.

Referring now to Figs. 10 to 12 the band is shown with a diaper of different form attached. Said diaper 27 is of the so-called "square" type, which is folded transversely as indicated at 28 and brought upwardly substantially equal distances at both front and rear. The lateral edges of said diaper or napkin are overlapped at each side of the wearer. In this instance the principal and, if desired, the only points of attachment of the diaper to the band are at the sides thereof, the elongated reinforcing patches 13 and 14 being provided at such points for this purpose.

The folded diaper is preferably carried up inside the band and the front and back folds secured together and to the band through said patches 13 and 14 as by means of the pins 29, 30 or other suitable fastening means. In addition the diaper may be and desirably is secured to the band at either the front or back center, or both. The fastener receiving tabs 6 and 7 may be reversed and folded up onto the band, or left down, or one tab may be reversed and the other left down, whichever arrangement is found most convenient and practical under the circumstances.

Accordingly in Fig. 10 I have shown the front tab 6 reversed and receiving a pin 31 or other fastener passing through said tab and adjacent band portion to secure the diaper, while in Fig. 11 the rear tab 7 as shown is in its lower position, receiving the pin or other fastening means 32.

It will now be apparent that in accordance with my invention I have provided an infant's shirt or band having fastener re-

ceiving reinforcing portions adapting the same band for use with widely varying styles of diaper and with various methods of attaching the same, rendering the garment universal in its diaper supporting function. If desired I may provide more than two such reenforcing portions shown herein. It will be observed that the band is structurally alike at both front and back rendering said band reversible whereby either face thereof may serve as front or as back as is most convenient, this being true in connection with any desired style of diaper or method of attachment.

15. The square diaper illustrated in Figs. 10 to 12 has been found of great advantage, as it gives the infant great comfort room and largely prevents chafing and the like. The weight of the diaper is more evenly distributed by the provision of at least four pins fastening points upon the band. Square diapers and the illustrated manner of securing them have been extensively endorsed by physicians and hospitals because of the additional room and general comfort afforded the infant wearer.

Having thus described my invention I desire it to be understood that my invention is not limited to the particular illustrative embodiments shown herein, the scope thereof being set forth in the following claims.

Claims:

1. An infant's shirt or band having a knitted body portion provided with a plurality of spaced depending tabs upon the lower edge thereof at front and rear, the lower edge of the garment between said tabs

being substantially straight, and a plurality of diaper supporting sections located and secured to said body portion at opposite sides of said body portion above the lower straight edge thereof and of substantially the same material as said body portion, said sections constituting means for attachment to the garment of diapers.

2. An infant's shirt or band having a knitted body portion formed as a seamless tube, the lower edge of the garment being substantially straight at the side portions at least thereof, and a plurality of diaper supporting sections located and secured to said body portion at opposite sides thereof above the lower straight edge of said side portions and of substantially the same material as said body portion, said sections constituting means for attachment to the garment of diapers.

3. An infant's shirt or band having a knitted, cylindrical body portion, the lower edge of the garment being substantially straight at the side portions at least thereof, and a plurality of diaper supporting portions at opposite sides of said body portion, extending upwardly from the lower straight edge of said side portions of the garment, and of the same material as said body portion and secured flatwise thereagainst, said upwardly extending portions providing reinforcing areas for the reception of diaper supporting means.

In testimony whereof, I have signed my name to this specification.

HARRIET LYONS REDMOND.
